[57] CLAIM

The ornamental design for a display stand, substantially as shown and described.

DESCRIPTION

FIG. 1 is a perspective view of the display stand showing my new design;

FIG. 2 is a front elevational view, the rear elevational view being identical thereto;

FIG. 3 is a side elevational view, the opposite side being identical thereto;

FIG. 4 is a partial sectional view taken along line IV—IV of FIG. 3; and

FIG. 5 is a partial sectional view taken along line V—V of FIG. 2.

The rear and opposite side of the stand are the same as the front and side shown, respectively.

FIG. 1

FIG. 2

FIG. 3

FIG. 4

FIG. 5
